BOTTLE

Nathan W. Schwartz, Bronx, N. Y.

Application November 15, 1951, Serial No. 17,414

Term of patent 14 years

(Cl. D58—6)

To all whom it may concern:

Be it known that I, Nathan W. Schwartz, a citizen of the United States of America, residing at Bronx, New York, county of Bronx and State of New York, have invented a new, original, and ornamental Design for a Bottle, of which the following is a specification, reference being had to the accompanying drawing, forming part thereof.

In the drawing:

Fig. 1 is a plan view of a bottle, showing my new design;

Fig. 2 is a front elevational view thereof; and
Fig. 3 is a rear view thereof.

I claim:

The ornamental design for a bottle, substantially as shown.

NATHAN W. SCHWARTZ.
